UNITED STATES PATENT OFFICE.

ALEXANDER ALLEN, OF PHILADELPHIA, PENNSYLVANIA.

UNION SUIT.

SPECIFICATION forming part of Letters Patent No. 613,953, dated November 8, 1898.

Application filed May 25, 1898. Serial No. 681,686. (No model.)

To all whom it may concern:

Be it known that I, ALEXANDER ALLEN, a citizen of the United States, residing in Philadelphia, Pennsylvania, have invented certain 5 Improvements in Union Suits, of which the following is a specification.

One object of my invention is to manufacture a union garment in such a manner that it will have an overlapping section at the 10 breast.

A further object is to make this overlapping portion of an independent section, and a still further object of the invention is to so make the opening that the garment can be readily 15 slipped on or off the wearer.

In the accompanying drawings, Figure 1 is a view of my improved union suit, illustrating my invention. Fig. 2 is a view of the unfinished body portion cut on the bias to form 20 the opening, and Fig. 3 is a triangular shield which is attached to the union suit and forms the overlapping breast portion.

Union suits opening from the center of the neck directly down are objectionable, as they 25 are apt to gap open, and the buttons confining the two portions together make it uncomfortable for the wearer. Suits having openings across the shoulders are objectionable, as they are uncomfortable and do not 30 allow of the free stretch of the material and are difficult to put on and take off. I overcome these objections in the following manner: A is the ordinary form of union suit, as shown in Fig. 2. I cut the body portion after 35 it is made on the line $\alpha\alpha'$, forming two edges $\alpha\alpha'$. To the edge α I secure the edge b of the triangular breast-piece B, Fig. 3, as shown in Fig. 1, and stitch this breast-piece securely to the garment, as shown, in such a manner 40 that its overlapping edge b' can be detachably secured to the garment near the opposite shoulder.

The garment is provided with buttons c , which are secured to the inner flap A' at the 45 points indicated in Fig. 1, and in the triangular breast-piece B are buttonholes b^2 in line with the buttons c , so that the outer flap of the breast-piece can be securely fastened to

the garment at the two edges and there will be no loose flaps. This gives a double protection to the chest, removes the buttons from the center to the sides, where they are not objectionable, and allows a large opening when the garment is unbuttoned, so that it can be readily applied or removed without danger 50 of tearing or straining the garment. Furthermore, the triangular breast-piece can be made perfectly plain or ornamented in the most elaborate manner, as it is made entirely independent of the garment and attached to 55 the garment after it has been completed.

It will be understood that hooks and eyes or other fastenings may be substituted for the buttons and that the buttons attaching the inner flap can be dispensed with if necessary. 60

While I have shown a full union suit, the arm and leg portions may be modified without departing from my invention, and in some instances may be used on undervests 70 or other underwear.

I claim as my invention—

1. The combination of a union garment having an opening in the body portion cut on the bias from the neck-opening toward the 75 waist, with a triangular shield secured to one edge of the garment at the opening and overlapping the other edge, substantially as described.

2. The combination in a union garment, of 80 the body having an opening cut from one side of the neck down to about the center of the waist, a triangular breast-piece secured to the garment at the edge of the opening and overlapping the garment at the breast, and 85 fastenings securing the inner edge of the garment to the breast-piece and the outer edge of the breast-piece to the garment, substantially as described.

In testimony whereof I have signed my 90 name to this specification in the presence of two subscribing witnesses.

ALEXANDER ALLEN.
